UNITED STATES PATENT OFFICE.

HERMAN S. HEICHERT, OF PITTSBURGH, PENNSYLVANIA, ASSIGNOR TO PITTSBURGH PLATE GLASS COMPANY, A CORPORATION OF PENNSYLVANIA.

PLATE-GLASS-POLISHING APPARATUS.

Application filed June 5, 1923. Serial No. 643,500.

To all whom it may concern:

Be it known that I, HERMAN S. HEICHERT, a citizen of the United States, and a resident of Pittsburgh, in the county of Allegheny and State of Pennsylvania, have made a new and useful invention in Improvements in Plate-Glass-Polishing Apparatus, of which the following is a specification.

The invention relates to apparatus for polishing plate glass, and particularly to that form in which the glass to be polished is carried beneath a series of polishers on cars or other carrier apparatus. After a certain period of use, the felts of the runners become caked with the rouge or other polishing material and their efficiency is reduced. The principal object of the invention is to provide a simple, convenient arrangement whereby the felts may be cleaned without removing the polisher blocks or discs from the machine. Certain embodiments of the invention are illustrated in the accompanying drawings wherein:

Figure 1 is a side elevation of the assembled apparatus. Fig. 2 is a fragmentary plan view at the edge of the runner frame. Fig. 3 is a section on the line III—III of Fig. 2. Fig. 4 is a view similar to that of Fig. 3, but showing the parts in a different position. Fig. 5 is an enlarged section on the line V—V of Fig. 4. And Figs. 6 and 7 are plan and side elevation views respectively showing a modification.

Referring to the general arrangement of parts as shown in Fig. 1, the reference numeral 1 designates the framework of the machine; 2 is a supporting bracket carried by the framework; 3 is a car mounted upon the track 4 and carrying the glass to be polished; 5 is a rack carried upon the bottom of the cars and driven from the shaft 6 through the gears 7 and 8; 9 is a tubular support provided at its upper and lower ends with bearings in which is journaled the runner shaft 10; 11 is an electric motor which drives the shaft 10 through the intermediary of gearing located in the casing 12; 13 is the runner frame secured to the lower end of the runner shaft and carrying the blocks or runners 14; 15 is a lever provided with a hooked end as indicated at 16 and engaging trunnions 17 carried by the gear casing 12; 18 is a link pivoted to the bracket 2 and provided with hook shaped ends 19 engaging trunnions 20 carried by the tubular support

9; 21 is a rod connected to the lever 15 for raising and lowering the runner, such rod being threaded as indicated at 22 and passing through the bracket 23; and 24 is a hand-wheel threaded onto the rod whereby it may be raised and lowered.

The arrangement whereby the blocks or runners may be cleaned will be seen by reference to Figs. 2 to 5. As here shown, the blocks are provided on their lower faces with the usual felts 25 and have secured to their upper sides the spindles 26 free to rotate in the bearings 27. The bearings 27 are pivotally mounted in brackets 28 projecting from the periphery of the runner frame 29 by means of the pins 30. When in operative position, as indicated at Fig. 3, the bearings are held securely against rotation about the pins 30 by means of other pins 31 also passing through the bearing and through the brackets 28.

The bearing is perforated to receive the pin 31 and this perforation is lined with a bushing 32, as indicated in Fig. 5 on which bushing is pivoted the dog or catch 33 which comes into play when the parts are moved to the position illustrated in Fig. 4. When it is desired to swing the runner to this position for cleaning purposes, the pin 31 is removed, which permits the bearing to swing outwardly about its pivot 30 until the spindle 26 is horizontal as indicated in Fig. 4, at which time the dog 33 engages a recess 34 in the periphery of the frame 29 so that the parts are automatically held in the position indicated in Fig. 4, after they have been swung to this position.

Mounted upon the splash wall 35 which parallels the track 4 on which the glass carrying trucks are mounted, is a cleaning pan or receptacle 36 in which the runners to be cleaned project. In order to swing the runner to the position indicated in Fig. 4, it is first necessary to raise the entire surfacing unit comprising the tubular support 9, the motor 11 and the runner frame 13 and this is accomplished by means of the lever 15 operated from the hand wheel 24. By this means the runner frame is lifted above the position indicated in Fig. 3 until the top of the bearing 27 comes in contact with the cotter pin 37 through the top of the spindle 26, after which the spindle and runner carried thereby are lifted to a point sufficiently above the table 3 to permit the run-

ner to swing out to the position indicated in Fig. 4. The pan 36 is preferably slid along the top of the wall 35 until it lies beneath the runner with its outlet 38 directed downwardly between the splash wall and the car. The felt 25 may now be cleaned in the usual way by applying water and by scrubbing the felt with a rough brush or other tool to loosen the rouge. When this runner is cleaned, the runner frame 13 is rotated to bring the next runner into position over the pan, after which it is cleaned in the same manner, the operation being repeated until the entire series of runners carried by the frame 13 are cleaned. After each runner is cleaned, the dog 33 is released and the runner permitted to drop back to the position of Fig. 3 at which time the securing pin 31 is inserted. This arrangement also permits 20 of the ready removal of the runner and spindle and its replacement by another runner and spindle in case any particular runner requires repair.

Figs. 6 and 7 illustrate an alternative arrangement in which the dog 33 is done away with. As here shown, the runner spindle 39 carrying the runner 40 passes up through a bearing 41 carried by the runner frame 42. This bearing is pivoted in the fork 43 by means of a pin 44 and the bearing is normally held against tilting movement by a second pin 45 also extending through the fork 43. When it is desired to clean the runner, the pin 45 is removed and the runner tilted about the pin 44 to the position indicated in dotted lines, which movement brings the upper perforation through the bearing into alignment with the perforations 46 through the fork 43. The parts are secured in this position by passing the pin 45 through the perforation in the bearing and through the perforation 46. The operation involved in manipulating the parts and cleaning the felts is the same as heretofore described. Various other arrangements might be provided for swinging the runners laterally so as to bring their faces in position for cleaning and for holding the parts in such position, the invention 50 contemplating broadly any and all means for swinging the runners laterally to cleaning position after the runner frame has been raised to permit this movement.

What I claim is:

1. In combination in apparatus for polishing plate glass, a rotatable runner frame mounted for vertical movement, means for raising and lowering said frame, means for rotating that frame, a carrier for the glass mounted for movement transversely of said frame and a plurality of polishing blocks or runners free to rotate about their vertical axes, and mounted on said frame so that they may be swung laterally away from the

center of said frame to present their lower surfaces in position for cleaning.

2. In combination in apparatus for polishing plate glass, a rotatable frame mounted for vertical movement, means for raising and lowering said frame, means for rotating the frame, a carrier for the glass mounted for movement transversely of said frame, a plurality of polishing blocks or runners free to rotate about their vertical axes and mounted on said frame so that they may be 75 swung laterally away from the center of said frame to present their lower surfaces for cleaning and releasable means for locking the blocks in both of their positions.

3. In combination in apparatus for polishing plate glass, a rotatable frame mounted for vertical movement, means for raising and lowering said frame, means for rotating the frame, a carrier for the glass mounted for movement transversely of said frame, a plurality of vertical bearings pivotally mounted in said frame so that they may be 80 swung laterally, a plurality of polishing blocks having spindles mounted in said bearings and releasable means for locking 85 the bearings in vertical position.

4. In combination in apparatus for polishing plate glass, a rotatable frame mounted for vertical movement, means for raising and lowering said frame, means for rotating the frame, a carrier for the glass mounted for movement transversely of said frame, a plurality of vertical bearings pivotally mounted in said frame so that they may be 90 swung laterally, a plurality of polishing blocks having spindles mounted in said bearings and releasable means for locking 95 the bearings in vertical position.

5. In combination in apparatus for polishing plate glass, a rotatable frame mounted for vertical movement, means for raising and lowering said frame, means for rotating the frame, a carrier for the glass mounted for movement transversely of said frame, a plurality of vertical bearings pivotally mounted in said frame so that they may be 100 swung laterally, a plurality of polishing blocks having spindles mounted in said bearings, releasable means for locking the bearings in vertical position, and releasable means for locking the bearings in position 105 after they have been swung laterally.

In testimony whereof, I have hereunto subscribed my name this 26th day of May, 1923.
